7 Claims. (Cl. 167—85)

This application is a continuation-in-part of my copending application Serial No. 509,399, filed May 8, 1955.

This invention relates to cosmetic preparations. More particularly it is directed to mascaras for eye lashes and eye brows.

These pigmented preparations are applied in a pasty state to the eyebrows and eyelashes and dry to form a film. It is essential that the mascara be of such a composition that it will not irritate the mucous membrane of the eyelid or other parts of the eye both at the time of application and after drying.

Preparations of this class are known which comprise emulsions of waxes with aqueous liquids containing, in addition, fats or fatty oils. Such compositions, however, dry only very slowly owing to their relatively high content of fatty substances and their tendency to smear. In consequence thereof, they are unsuitable for application to eye lashes. It has been proposed to use for such purposes, compositions comprising aqueous emulsions of waxes which contain a volatile oil, particularly turpentine, instead of a fat or fatty oil. These latter compositions provided much better adherence because the turpentine evaporated soon after the application of the composition, leaving a fine water insoluble film.

It has been found, however, that those preparations were effective only if they contained at least 50% of turpentine. However, when the turpentine is present in such high concentration, the presence thereof is readily observed because of its odor. Furthermore, its use is particularly objectionable because of its known irritating effect on the skin and eyes. Attempts to reduce the turpentine content and to increase, for example, the water content, resulted in products which became so brittle in a short while that the compositions crumbled away.

It has been found that the aforesaid disadvantages arising from preparations based on a high turpentine content can be avoided by the use of a cosmetic composition containing substantially less turpentine, i.e., at most about one-half of the turpentine previously used. The novel composition of this invention comprises an aqueous emulsion of a suitable wax and turpentine in combination with a mixture of a drying oil and a fatty non-drying oil.

Small additions of turpentine, castor oil and linseed oil have been disclosed before only for a hair treating compound, which is absolutely anhydrous and has a strictly fatty base and is intended to increase the softness and luster of the hair of the head. Owing to its high tendency to smear, such a fatty cream is not suitable for cosmetic paint. In a wax-containing aqueous paint emulsion such a combination has not been used before and offers additional advantages over the known compositions of that type.

I have discovered that the presence, in the instant cosmetic composition of a drying oil, such as linseed oil, results in the drying of the applied composition even when the content of the volatile oil, such as turpentine, is small; and thus prevents any subsequent smearing or adhesion of the eye lashes. Furthermore, presence in the compo-

2

sition of a non-drying fatty oil imparts requisite flexibility to the residual film after evaporation of the highly volatile component.

Waxes suitable for use in the composition are those 5 customarily employed, e.g., beeswax, ceresin, Japan vegetable wax and the like.

Fatty oils (non-drying) suitable for imparting the desired flexibility are typified by castor oil, olive oil, sunflower seed oil, palm kernel oil and the like. Castor oil 10 is preferred because it is most readily emulsified.

The emulsification is effected by higher fatty alcohols or the sulfonates thereof or mixtures thereof.

The compositions contain suitable pigmenting materials and may also include essential oils and perfume bases to 15 impart a fragrance.

The mascaras of this invention are prepared by emulsifying the several components with the addition of customary pigmenting substances and perfumes; and also, if desired, a substance which acts as a perfume base, such as 20 terpineol. It is also suitable to admix an emulsifying agent to obtain a perfectly homogeneous mixture. In this connection, it is to be noted, that the usual water-soluble emulsifying agents, e.g., borax or triethanolamine have 25 been found unsuitable, due to the high content of water required.

I have found that higher fatty alcohols such as cetyl alcohol and fatty alcohol mixtures known under the trademark Lanette, which may contain fatty alcohol sulfonates or fatty alcohol phosphates, or higher fatty alcohol sulfonates themselves or cholesterol esters may be used advantageously as emulsifying agents.

The following are examples in accordance with the invention:

Example 1

35 This composition (suitably pigmented) contains the following ingredients:

	Percent by weight
Beeswax	29
40 Oil of turpentine	11
Eucalyptus oil	6.6
Linseed oil	5.5
Castor oil	5
Lanette-N	6.6
45 Terpineol	3.3
Water	33
	100.00

50 The composition is prepared in the customary fashion by effecting emulsification of the aforesaid ingredients, including the incorporation of a suitable pigmenting substance such as is used in this art, as well as perfumes, if desired.

Example 2

55 This composition (suitably pigmented) contains the following ingredients:

	Percent by weight
Beeswax	20
60 Oil of turpentine	15
Linseed oil	7
Castor oil	5
Lanette-N	10
Terpineol	3
65 Water	40
	100.00

The composition is prepared as described in Example 1.

3
Example 3

This composition (suitably pigmented) contains the following ingredients:

	Percent by weight
Beeswax	26
Oil of turpentine	20
Linseed oil	7
Castor oil	6
Lanette-N	8
Terpineol	3
Water	30
	100.00

This composition is prepared as described in Example 1.

The amounts of the essential ingredients present in the mascara base (the aforesaid aqueous emulsion of the waxes and other components) of this invention are as follows:

	Approximate percent by weight
Wax content	20-40
Volatile oil	10-24
Emulsifying agent	5-15
Drying oil	5-15
Non-drying fatty oil	1-10
Water	20-50

Suitable pigmenting substances are for example those belonging to the class of indulines such as the commercially available "nigrosines."

The emulsifying agent used in the examples was the commercially available "Lanette-N." For the chemical composition of the different types of "Lanettewachs" refer to H. Römpf, *Chemielexikon*, vol. II, 4th ed., page 2545, Frankh'sche Verlagsbuchhandlung, Stuttgart (1958).

While I have shown and described what I believe to be the best embodiments of my invention, it will be apparent to those skilled in the art that various changes and modifications may be made therein without departing from the spirit and scope of the invention as defined in the appended claims.

What is claimed is:

1. A mascara comprising:

	Percent by weight
Wax	20-40
Turpentine	10-24
An emulsifier selected from the group consisting of the higher fatty alcohols, the sulfonates thereof and mixtures of said alcohols and sulfonates	5-15
Linseed oil	5-15
Non-drying fatty oil	1-10
Water	20-50

and non-toxic pigmentation, said mascara being an aqueous emulsion having a pasty consistency and being acceptable to the eyelash portions of the eyelids without causing irritation of the mucous membranes of the eyelids or irritation of the eye.

2. A mascara comprising:

	Percent by weight
Beeswax	20-40
Turpentine	10-24
An emulsifier selected from the group consisting of the higher fatty alcohols, the sulfonates thereof and mixtures of said alcohols and sulfonates	5-15
Linseed oil	5-15
Castor oil	1-10
Water	20-50

and non-toxic pigmentation, said mascara being an aqueous emulsion having a pasty consistency and being acceptable to the eyelash portions of the eyelids without causing irritation of the mucous membranes of the eyelids or irritation of the eye.

3. A mascara comprising:

	Percent by weight
Beeswax	29
Turpentine	11
Eucalyptus oil	6.6
Linseed oil	5.5
Castor oil	5
An emulsifier selected from the group consisting of the higher fatty alcohols, the sulfonates thereof and mixtures of said alcohols and sulfonates	6.6
Terpineol	3.3
Water	33

and non-toxic pigmentation, said mascara being an aqueous emulsion having a pasty consistency and being acceptable to the eyelash portions of the eyelids without causing irritation of the mucous membranes of the eyelids or irritation of the eye.

4. A mascara comprising:

	Percent by weight
Beeswax	20
Turpentine	15
Linseed oil	7
Castor oil	5
An emulsifier selected from the group consisting of the higher fatty alcohols, the sulfonates thereof and mixtures of said alcohols and sulfonates	10
Terpineol	3
Water	40

and non-toxic pigmentation, said mascara being an aqueous emulsion having a pasty consistency and being acceptable to the eyelash portions of the eyelids without causing irritation of the mucous membranes of the eyelids or irritation of the eye.

5. A mascara comprising:

	Percent by weight
Beeswax	26
Turpentine	20
Linseed oil	7
Castor oil	6
An emulsifier selected from the group consisting of the higher fatty alcohols, the sulfonates thereof and mixtures of said alcohols and sulfonates	8
Terpineol	3
Water	30

and non-toxic pigmentation, said mascara being an aqueous emulsion having a pasty consistency and being acceptable to the eyelash portions of the eyelids without causing irritation of the mucous membranes of the eyelids or irritation of the eye.

6. A mascara comprising:

	Percent by weight
A wax base selected from the group consisting of beeswax, ceresin and Japan vegetable wax	20-40
Turpentine	10-24
An emulsifying agent selected from the group consisting of the higher fatty alcohols, the sulfonates thereof and mixtures of said alcohols and sulfonates	5-15
Linseed oil	5-15
A readily emulsifiable flexibility imparting agent which is a non-drying oil selected from the group consisting of castor oil, olive oil, sunflower seed oil and palm kernel oil	1-10
Water	20-50

and non-toxic pigmentation, said mascara being an aqueous emulsion having a pasty consistency and being acceptable to the eyelash portions of the eyelids without causing irritation of the mucous membranes of the eyelids or irritation of the eye.

7. A mascara comprising:

	Percent by weight	
Beeswax	20-29	
Oil of turpentine	11-20	1,638,709 8/1927 Schneider ----- 167-90
Eucalyptus oil	0-6.6	2,134,494 10/1938 Winterstein ----- 167-85
Linseed oil	5.5-7	
Castor oil	5-6	
An emulsifier selected from the group consisting of higher fatty alcohols, the sulfonates thereof and mixtures of said alcohols and sulfonates	6.6-10	Artist Handbook, Viking Press, 1943, pp. 108-110, 187-197, 298, 299, 362, 363, 364-368.
